UNITED STATES PATENT OFFICE.

SOLOMON R. DRESSER, OF BRADFORD, PENNSYLVANIA.

DESIGN FOR A CLAMPING-RING FOR PIPE-COUPINGS.

SPECIFICATION forming part of Design No. 35,618, dated January 28, 1902.

Application filed December 14, 1901. Serial No. 85,991. Term of patent 14 years.

To all whom it may concern:

Be it known that I, SOLOMON R. DRESSER, a citizen of the United States, residing at Bradford, in the county of McKean and State 5 of Pennsylvania, have invented and produced a new and original Design for Clamping-Rings for Pipe-Couplings; and I do hereby declare the following to be a full, clear, and exact description of the same, reference being had to the accompanying drawings, forming a part thereof.

Figure 1 represents a face view of my design, and Fig. 2 represents a central section through the same.

15 My design consists of a ring having a cylindrical peripheral edge *a* and parallel faces *b* and *c*. The face *b* is flat and is provided with a central aperture *b'* and with a series of smaller apertures *b*², arranged concentrically

around said central aperture. The face *c* is 20 provided with a central recess *c'*, concentric with and of greater diameter than aperture *b'*, said recess extending from the face *c* to the aperture *b'*, adjacent to which its walls are curved inwardly. Around the recess *c'* the 25 face *c* is provided with a series of recesses *c*², separated by radial webs *c*³.

What I claim, and desire to secure by Letters Patent, is—

The design for a clamping-ring for pipe- 30 couplings, substantially as described.

In testimony whereof I affix my signature in presence of two witnesses.

SOLOMON R. DRESSER.
